UNITED STATES PATENT OFFICE.

JOHN T. NIXON AND DANIEL N. CRESS, OF LEXINGTON, MISSISSIPPI.

COTTON-GIN.

SPECIFICATION forming part of Letters Patent No. 331,729, dated December 1, 1885.

Application filed July 14, 1885. Serial No. 171,610. (No model.)

To all whom it may concern:

Be it known that we, JOHN TYLER NIXON and DANIEL NICHOLAS CRESS, both of Lexington, in the county of Holmes and State of 5 Mississippi, have invented certain new and useful Improvements in Cotton-Gins, of which the following is a full, clear, and exact description.

Reference is to be had to the accompanying 10 drawings, forming part of this specification, in which similar letters of reference indicate corresponding parts in all the figures.

Figure 1 is a side elevation, partly in section, of a part of a cotton-gin to which our 15 improvement has been applied. Fig. 2 is a sectional plan view of the same, taken through the broken line $x\ x$, Fig. 1. Fig. 3 is a plan view of one end of the brush-shaft, and showing a journal-box in section.

20 Our invention relates to improvements in cotton-gins; and it consists in the peculiar construction and arrangement of parts, all as hereinafter fully described, and pointed out in the claims.

25 A represents the frame of a cotton-gin. B are the gin-saws, and C is the saw-shaft, which revolves in bearings attached to the frame A in the ordinary manner. To one 30 end of the saw-shaft C are attached a fast pulley, D, and a loose pulley, E, to receive a driving-belt from a steam-engine or other suitable power.

F is the brush to remove the lint from the 35 saws B, and G is the brush-shaft. To the journals of the brush-shaft G are attached, or upon them are formed, V-shaped collars H, which revolve in correspondingly - shaped 40 grooves in the journal-boxes I, to hold the brush-shaft G and the brush F from longitudinal movement. Upon the opposite sides of the journal-boxes I, and at an angle of about forty-five degrees (45°) with the horizontal plane of the gin, are formed gudgeons J, which 45 oscillate in bearings K in the bearing-blocks L, so as to allow the journal-boxes I to rock, and thus prevent the journals of the brush-shaft from binding in their bearings should the said brush-shaft spring. The bases of the 50 bearing-blocks L slide in grooves in plates M, attached to side bars of the frame A. To the

outer ends of the bearing-blocks L are attached the inner ends of rods N, which pass through holes in the posts of the frame A, and have screw-threads upon their outer ends to receive the nuts O, so that the inward movement of 55 the bearing-blocks L can be regulated and limited by adjusting the said nuts O. Upon the screw-rods N are placed spiral springs P, the outer ends of which rest against the inner sides of the posts of the frame A, and their 60 inner ends rest against shoulders, collars, or nuts Q, formed upon or attached to the said rods N, or against the outer ends of the bearing-blocks L.

To the end parts of the brush-shaft G are 65 attached small friction-wheels R, the faces of which bear against the faces of the large friction-wheels S, attached to the saw-shaft C, so that the brush will be driven from the saw-shaft by friction.

70 With this construction there are no belts to slip and burn out, so that the brush will be driven at a uniform velocity, and can be driven up to its full speed.

Having thus described our invention, what 75 we claim as new, and desire to secure by Letters Patent, is—

1. In a cotton-gin, the combination, with the frame A and the saw-shaft C, provided with the large friction-wheels S, of the brush-shaft G, provided with the small friction-wheels R, the bearing-blocks L, the screws N, nuts O, and springs P, substantially as herein 80 shown and described.

2. In a cotton-gin, the combination, with 85 the frame A and the journals of the brush-shaft G, having V-shaped collars H, of the grooved journal-boxes I, having gudgeons J, the bearing-blocks L, having gudgeon-bearings K, the screw-rods N, nuts O, and spiral 90 springs P, substantially as herein shown and described, whereby the inward movement of the bearing-blocks can be limited and the brush-shaft can spring without binding in its bearings, as set forth.

JOHN T. NIXON.
DNL. N. CRESS.
